COMBINED CLOCK AND MULTIPLE PICTURE FRAME

Benjamin G. Edelman, Brooklyn, N.Y., assignor to United
Metal Goods Manufacturing Co., Inc., Brooklyn, N.Y.,
a corporation of New York

Filed Nov. 1, 1968, Ser. No. 14,284

Term of patent 3½ years

Int. Cl. D10—01
U.S. Cl. D42—7

FIG. 1

FIG. 2

FIG. 3

FIG. 1 is a front elevational view of a combined clock and multiple picture frame showing my new design;

FIG. 2 is a top plan view; and

FIG. 3 is a rear elevational view.

The broken line showings of pictures are for illustrative purposes only.

I claim:

The ornamental design for a combined clock and multiple picture frame, substantially as shown and described.
